UNITED STATES PATENT OFFICE.

WILLIAM SIBERT WITTER, OF TOLEDO, IOWA.

SPARK-PLUG.

1,092,322.

Specification of Letters Patent. Patented Apr. 7, 1914.

Application filed January 6, 1912. Serial No. 869,652.

To all whom it may concern:

Be it known that I, WILLIAM SIBERT WITTER, a citizen of the United States, residing at Toledo, in the county of Tama and State of Iowa, have invented certain new and useful Improvements in Spark-Plugs, of which the following is a specification, reference being had to the accompanying drawings.

10 This invention relates to spark plugs and more particularly to an attachment for providing a plurality of spark gaps in series with the main electrodes of a spark plug.

The main object of this invention is to 15 provide an attachment for spark plugs which can be readily placed in position on the same without necessitating the removal or dismantling of any of the main parts of this spark plug.

20 Another object of this invention is to have this attachment arranged so that it may be manufactured at a relatively low cost.

A further object of this invention is to 25 provide a suitable type of spark plug for the attachment in question.

Still another object of this invention is 30 to arrange the spark plug and the attachment in question in such a manner as to permit all necessary adjustment for the purpose in question, to be readily made.

Other objects of this invention will 35 become apparent as it is more fully set forth.

In the device referred to in this application, means are provided whereby the same 40 may be readily inserted in to a spark plug arranged to receive it, and adjusted to suit the conditions arising. Further the device is arranged so that it may be moved in such a way as to provide other points to which the sparks may be jumped from the electrodes in question, should it be desirable to do so.

In the construction shown in the drawings, Figure 1 represents a view in elevation of a spark plug embodying this invention. Fig. 2 is a central sectional elevation of Fig. 1. Fig. 3 is a detail view of a modification hereinafter specifically referred to.

Similar reference characters refer to similar parts throughout the drawings.

In the construction shown in the drawings, 1 represents a contact nut used for fastening a conductor against another nut 2, both of which are threaded on a central conductor 15.

3 is a core made of any suitable insulat-

ing material which has its lower portion recessed as shown in Fig. 2, and is provided with an enlarged portion 14, in order that it may be held in position with respect to the other parts usually used in a spark plug. A gland nut 4 is disposed on the upper portion of the core 3 and threadably engages with a shell 5, whose lower portion extends underneath the enlarged portion 14 of the core, and suitable washers or packings 13 are placed above and below the enlarged portion 14 so that the gland nut 4 and the inwardly extending portion of the shell can engage therewith. The lower portion 6 of the shell is exteriorly threaded in order to permit the spark plug to be readily placed within a combustion engine or the like in the usual manner, and the portion of the shell above the threaded portion is enlarged 75 in the usual manner as is clearly shown in Figs. 1 and 2.

The central primary electrode 15 has its upper portion threaded as is clearly shown in Fig. 2, and its lower portion enlarged as 80 shown at 12, in order that means may be provided for holding the conductor securely to the core 3. A suitable contact member 9 forms part of the conductor 15 and projects downwardly through the recessed portion of the core, and its lower portion is hooked or bent as is clearly shown in Fig. 2 85 in order to come adjacent to the inside surface of the intermediate electrode 8, which will be referred to in detail in a later part 90 of the specification. The upper portion 11 of the electrode 8 is arranged to threadably engage in the threaded recessed portion of the core, so that it will be held securely thereby, and in a proper position in relation to the contact member 9, and an electrode 10, which is secured to the shell.

It will be noticed by referring to the drawings, that the electrode 8 provides a means for giving a plurality of spark gaps 100 to the spark plug, between the shell and intermediate electrodes, and also that the intermediate electrode is of such a form, as to permit it being adjusted or moved so as to produce different points for the spark to 105 jump to from the electrodes just mentioned. The lower portion of the shell is interiorly enlarged in order to permit the lower portion of the core to readily expand under the action of the heat in the combustion chamber 110 in which it is placed, and also to permit the lower portion of the core to be heat-

ed on all sides, thereby eliminating any injurious strains that might otherwise occur. It is of course understood that the electrode 8 is hollow and of sufficient interior diameter to permit the primary electrode to easily pass therethrough, and at the same time sufficiently spaced apart from it to prevent sparks jumping from the primary electrode to the intermediate electrode, except where the provision is especially made for the spark gap. The general operation of the device is well known, so that no further description will be made of the same.

The lower portion of the core is provided with a collar or bead 7, which is clearly shown in the drawings. This bead serves for the purpose of strengthening the core at the portion where the greatest heat strains are placed upon it, and also serves for the purpose of supporting electrodial members. These types of electrodial members are not shown or described in this application, but reference is made to the main purpose for which the bead 7 is indicated in order to more clearly indicate its use.

In Fig. 3 a type of attachment is shown which is similar to that shown in Fig. 2. It is hollow, and its upper portion 11 is threaded and a slot 16 is provided longitudinally therein and its lower portion is flared.

Each one of these forms have special advantages, but it can be readily noted that their cost of manufacture is comparatively small and that there is no difficulty in installing them in the spark plug in question, and that this may be done without dismantling the spark plug in any way. The

attachment shown in Fig. 3 can be readily turned in case it is beneficial to provide different points to which the spark may be jumped from the electrodes 9 and 10. The threaded engagement of the parts permits a certain amount of vertical adjustment of the attachment, which will permit a relatively great amount of adjustment in the spark gaps 18 and 19.

Having thus described this invention, what is claimed is:—

A spark plug, comprising a shell, an insulating core mounted in said shell and formed at one end with a longitudinally disposed interiorly threaded socket, a tubular intermediate electrode formed with screw threads engaging the screw threads of the socket, whereby the said electrode may be turned and simultaneously moved into and out of the socket, an electrode secured to the shell and extending toward the edge of the intermediate electrode, said intermediate electrode having such edge outwardly flared, and a primary electrode secured in the core and extending down through and spaced from the tubular intermediate electrode and formed with a contact point extending away from the shell electrode and toward the flared edge of the intermediate electrode at a point opposite to the shell electrode.

In testimony whereof I hereunto affix my signature in the presence of two witnesses.

WILLIAM SIBERT WITTER.
